FINISHING WHEEL

Filed Jan. 4, 1929

Inventor:
Frederick C. Simmons,
By *Hobsondale*
Attorney.

UNITED STATES PATENT OFFICE

FREDERICK C. SIMMONS, OF HIGHLAND PARK, PENNSYLVANIA, ASSIGNOR TO PIO-
NEER SUSPENDER COMPANY, A CORPORATION OF PENNSYLVANIA

FINISHING WHEEL

Application filed January 4, 1929. Serial No. 330,381.

The invention relates to finishing wheels; the object is to provide an improved wheel for finishing the edges of fibrous material, especially the edges of leather belts.

5 The device comprises in general the well known wire buffing wheel or brush clamped between two rigid discs but in accordance with the present invention, so that the peripheries of the discs will extend to or slightly beyond the periphery of the wire brush. The 10 periphery of the brush so clamped is then ground to form an annular peripheral semi-circular channel to conform to the required final finished cross-sectional contour of the 15 belt edge.

Referring to the drawings, which illustrate merely by way of example, suitable means for the embodiment of my invention:—

Fig. 1 is a cross-section on line 1, 1 of Fig. 2.
20 Fig. 2 is a plan view with the nut removed and part of one plate and also part of the brush removed.

Similar numerals refer to similar parts throughout the several views.
25 The brush 5, used in this device may be of the usual commercial type, consisting of a hub 6 and the wire retaining parts 7 and 8, from the center of which the wires radiate. This brush is clamped between the two plates 30 or discs 9 and 10, by means of the blocks or washers 11 and 12, all carried on the threaded end of shaft 13 having the shoulder 14 for engaging the outer margin of block or washer 12. A nut 15 is screwed down on the other 35 block or washer 11. These blocks or washers 11 and 12 may of course be made integral with the discs 9 and 10, if desired. The discs 9 and 10 are also concentrically recessed on their inner faces, as at 16 and 17, to receive 40 the hub 6 and other wire securing elements 7 and 8, so that the portions of the discs at and near their margins may effectually clamp the two sides of the brush at the periphery thereof and for some distance therefrom.

45 The brush is clamped at and near its periphery as tightly as is reasonably practicable. This however does not prevent a limited movement of the wires at the periphery, especially in planes of their rotation.

50 When the brush has been so clamped be-

tween the discs 9 and 10, the periphery of the brush is ground so as to form an annular semi-circular channel or groove 18, therein corresponding to the required cross-sectional contour of the belt edge when finished. 55

In operation.—When the leather belt has been properly or suitably beveled, by cutting or grinding away the corners of the belt edges, certain filaments or feathers of the fibrous material remain attached to the edge, 60 and the finishing wheel, in accordance with the present invention, serves to remove such adhering parts and gives the belt a smooth clean finish in desired cross-sectional contour.

The centrifugal action of the wheel, due 65 to the peculiar supporting means for the wire strands or bristles, which restrains their lateral spread serves effectively to throw off the fibers or particles removed from the belt, and thus the periphery of the wheel remains 70 clean and unclogged by such waste material.

The means for restraining said lateral spread of the wire strands, in combination with the grooved periphery of the brush, 75 greatly facilitates the proper finishing of the belt edge in required contour, and also adds materially to the effective life of the finishing wheel.

What I claim is:—

1. In a device of the character described, 80 a brush having a semi-circular peripheral channel comprising bristle-like strands radiating from a substantially common center, means for clamping both sides of the brush at its periphery to limit the lateral displacement of the said strands, and means for supporting and rotating the same. 85

2. In a device of the character described, 90 a brush having a circular contour comprising bristle-like strands radiating from a substantially common center, said brush having a grooved peripheral surface, means for clamping both sides of the bristle like strands, said means extending to and beyond the brush periphery to limit the lateral displacement of the said strands, and means for supporting and rotating the same. 95

3. In a device of the character described, 100 a wire brush having a channeled hub and wire bristle-like strands radiating therefrom a

pair of discs for clamping the brush therebetween, and a supporting shaft and a nut threaded thereon for exerting pressure on the discs, the said discs having their peripheries extending slightly beyond the periphery of the brush.

4. In a device of the character described, a wire wheel brush having a channeled hub and wire bristle-like strands radiating therefrom, a pair of discs for clamping the brush therebetween, and a supporting shaft and a nut threaded thereon for exerting pressure on the disc, the said discs having their peripheries extending slightly beyond the periphery of the brush and the peripheral surface of the brush formed with a semi-circular channel.

5. In a device of the character described, a wire wheel brush having a channeled hub and wire retaining devices associated therewith, wire bristle-like strands radiating therefrom, a pair of discs for clamping the brush therebetween at and adjacent the periphery thereof, having recesses on their inner faces for receiving the hub and wire retaining devices, and a supporting shaft and a nut threaded thereon for exerting pressure on the discs.
